[57] CLAIM

The ornamental design for closure for a container, as shown and described.

DESCRIPTION

FIG. 1 is an elevational view of an embodiment of a closure according to my design, the side not shown being the same as the side shown;

FIG. 2 is a top plan view of the closure of FIG. 1;
FIG. 3 is a bottom plan view of the closure of FIG. 1;
FIG. 4 is an elevational view of an alternative embodiment of a closure according to my design;

FIG. 5 is a top plan view of the closure of FIG. 4; and,
FIG. 6 is a bottom plan view of the closure of FIG. 4.
